UNITED STATES PATENT OFFICE.

CHARLES R. DE BEVOISE, OF NEWARK, NEW JERSEY.

DRESS-FORM.

1,081,814.

Specification of Letters Patent.

Patented Dec. 16, 1913.

Application filed July 6, 1910. Serial No. 570,652.

To all whom it may concern:

Be it known that I, CHARLES R. De Bevoise, a citizen of the United States, residing at Newark, in the county of Essex and State of New Jersey, have invented new and useful Improvements in Dress-Forms, of which the following is a specification.

The present invention comprehends the production of a dress form comprising a pair of Shirred ruffles attached to an under-garment to rectify defects in the human figure, the ruffles being so constructed as to admit of their being drawn up into puffs or shirrs, in order to produce fullness at the required points. These ruffles are designed primarily for attachment to the inside or inner face of the garment, so as to fill out the latter, and to be, to all intents, incapable of detection. They are, moreover, especially intended to be worn as a part of a form-fitting upper garment, from which they are readily detachable for laundrying purposes.

A practical embodiment of the invention is illustrated in the accompanying drawings, 25 wherein:

Figure 1 is an elevation of the improved article of apparel, taken from the inner side thereof, one of the ruffles being shown in raised position. Fig. 2 is an enlarged sec- 30 tional view of one of the ruffles.

In the construction illustrated, the two ruffles, which are generally indicated by the numerals 1, 1, are shown as employed in connection with a form-fitting upper garment 2 of the type known as a brassière or corset cover, this garment preferably having the particular construction described in my prior application, Serial No. 500,999, filed June 9, 1909. The two ruffles are arranged upon the inside of the garment, and they are attached to the upper edge of the latter at their upper corners, as indicated by the numerals 3 and 4, their lower edges being free. The arrangement specified results in the presence of the ruffles being practically incapable of detection, when the garment to which they are attached, is being worn. It has also the further result that said ruffles are rendered capable of being raised into the position shown at the right of Fig. 1 for laundrying purposes. This is equally true whether the attaching medium be in the form of stitching, or of ribbons which are run through said ruffles and the body garment at the points mentioned. In the latter

instance, moreover, the ruffles may, if desired, be completely detached from the body garment. In either case, the ruffles are held in place, when in use, by means of tapes, ribbons or the like 5 and 6, which are attached to the front side seams 7 of the body garment, and are adapted to be tied to the adjacent ends of the lower and central draw-strings or tapes 8 and 9 of said ruffles.

As regards the construction of the ruffles, 65 it may be stated that each comprises a series of strips of muslin or lawn which overlie and overlap one another. The innermost or body strip 10 of each ruffle, that is to say, that strip which is closest to the body of the 70 wearer, has its lower edge formed with a hem 11, wherein the draw-string or tape 8 is arranged. The next strip 12 is folded horizontally upon itself, so as to provide a pair of flounces 13 of unequal widths, and 75 is attached to strip 10 at the line of fold by two spaced rows of stitches 14 between which is arranged the main or central draw- 80 string 9, the rows of stitches being approxi- mately midway of said strip 10. The inner flounce or fold of this strip overlies the lower portion of strip 10, as shown in Fig. 2. The succeeding strip 15 is folded in a manner similar to that above described, to provide the two folds or flounces 16, and said 85 strip is likewise attached to strip 10 by two rows of stitches 17 which receive between them a draw-string or tape 18 and are located approximately midway between the 90 stitches 14 and the upper edge of strip 10. The inner fold or flounce 16 of strip 15 overlaps the outer fold or flounce 13, and the outer fold or flounce of this strip is overlapped, in turn, by a single flounce or strip 19 attached to the upper edge of strip 10 by 95 spaced rows of stitches 20 between which is likewise arranged a draw-string 21. The strips 12, 15, and 19 are attached to the body strip 10, as described, and are disposed between said body strip and the inner face of 100 the brassière, in unattached relation, how- ever, to said inner face.

The strips 12, 15 and 19 take up an area which is substantially equal to the area of the strip 10 and, together with the latter, 105 are plaited longitudinally, prior to their disposition in the manner above described, the arrangement being such that the plaits will fit or nest within each other to a cer- 110 tain extent. Consequently, when the draw-

strings are tightened, the nests of plaits will be drawn together so as to constitute vertical puffs 22, as shown in connection with the left-hand ruffle in Fig. 1, the puffs being contracted centrally and at their ends. The extent of projection of the puffs outwardly from the garment is, of course, dependent upon the extent to which the draw-strings are tightened, this being a matter entirely under the control of the wearer.

From the foregoing, it will be apparent that when the garment is in actual use, it will be filled out from the inside by the two ruffles, thereby imparting to the wearer the appearance of having a perfectly developed bust, this being due to the employment of the ruffles, which act as pads and are capable of a slight adjustment by means of the drawstrings or tapes. As originally stated, the outer ends of the draw-strings or tapes 8 and 9 are tied to the tapes 5 and 6, the inner mutually adjacent ends of the former strings or tapes being tied together, as are those of the upper strings or tapes 18 and 21.

The number of strips of which each ruffle is composed is obviously variable, according to circumstances, but it is evident that by folding over certain of said strips in the manner described above, such number is materially decreased, since each of the strips so folded thus constitutes in effect a pair of strips, thereby reducing the initial cost of production to a considerable extent. The utility of the garment is, moreover, increased by employing a pair of separate ruffles rather than a single continuous ruffle, since each ruffle is thus susceptible of adjustment independently of the other ruffle, and may be removed when torn or otherwise injured without necessitating the other ruffle being likewise removed. Finally, the arrangement of the strips 12, 15 and 19 between the body strip 10 and the body garment or brassière has the effect of filling out said garment more perfectly and to a greater extent than if such arrangement were reversed and the body strip disposed directly against the body garment.

I claim as my invention:

1. A dress form comprising a brassière, and a ruffle associated therewith, and consisting of a body strip which is attached to the inner face of the brassière, a plurality of overlapping strips superimposed on the body strip and disposed between the same and said inner face in unattached relation to the latter, all of the said strips having nested vertical plaits and a plurality of transversely arranged draw strings for drawing the nested plaits into puffs of desired extent, the body strip having an area

which is substantially equal to the area taken up by said overlapping strips.

2. A dress form comprising a brassière and a ruffle associated therewith and made in structurally independent sections, the sections being separately secured to the inner front face of the brassière at each side thereof and each comprising a body strip which is attached to said inner face, a plurality of overlapping strips superimposed on the body strip and disposed between the same and said inner face in unattached relation to the latter, all of the said strips having nested vertical plaits and a plurality of transversely-arranged draw strings for drawing the nested plaits into puffs of desired extent, the body strip having an area which is substantially equal to the area taken up by said overlapping strips.

3. A dress form comprising a brassière and a ruffle associated therewith and consisting of a body strip which is attached to the inner face of the brassière, a plurality of overlapping strips superimposed on the body strip and disposed between the same and said inner face in unattached relation to the latter, each of the overlapping strips being horizontally folded and being attached to the body strip adjacent its line of horizontal folding, all of said strips having nested vertical plaits and a plurality of draw strings for drawing the nested plaits into puffs of desired extent, the body strip having an area which is substantially equal to the area taken up by said overlapping strips.

4. A dress form comprising a brassière and a pair of structurally independent ruffles associated with the inner face thereof, the ruffles being located at each side of the brassière and each comprising a body strip attached at its upper edge to said inner face, a plurality of vertically plaited strips secured in overlapping relation upon the body strip for disposal adjacent the inner face of the brassière but unattached to the latter, the said vertically plaited strips taking up an area which is substantially equal to the area of said body strip, and draw strings for gathering the plaits into puffs, the brassière having suitably located tapes to which the outer ends of the draw strings are tied, the mutually adjacent inner ends of the draw strings being tied to one another.

In testimony whereof I have hereunto set my hand in presence of two subscribing witnesses.

CHARLES R. DE BEVOISE.
